UNITED STATES PATENT OFFICE.

ACHILL BIPPIANI, OF NEWARK, NEW JERSEY.

SAFETY-RAZOR.

1,078,989.

Specification of Letters Patent Patented Nov. 18, 1913.

Application filed June 20, 1912. Serial No. 764,393.

To all whom it may concern:

Be it known that I, ACHILL BIPPIANI, a citizen of the United States, residing at 36 Ingraham Place, Newark, county of Essex, and State of New Jersey, have invented certain new and useful Improvements in Safety-Razors, fully described and represented in the following specification and the accompanying drawings, forming a part of the same.

The present invention relates to a safety-razor in which a thin sheet-metal blade is held in a blade-carrier having a cylindrical back and elastic gripping flanges. The construction is especially adapted for making the parts of elastic sheet-metal by punching and stamping.

The razor-head or body is formed with a comb and clamping-plate integral with one another and provided with cylindrical curves forming a bore adapted to receive the back of the blade-carrier when the latter is inserted longitudinally. The comb and clamping-plate are preferably connected by a loop at one side of the said bore, the sides of which loop are adapted to yield when the blade-carrier is inserted in such bore.

The comb-plate is, as usual, extended beyond the edge of the blade, and the clamping-plate is preferably extended nearly to the edge of the blade so that the blade projects slightly between the two, and the clamping-plate is thus enabled to operate as a guard in shaving, in addition to the guard furnished by the comb.

A threaded socket or nut is affixed to the outer side of the comb at a suitable angle to hold the razor when shaving, and the back of the blade-carrier is made cylindrical to receive nuts corresponding to the nut upon the comb, and the handle is formed with a screw-end adapted to fit interchangeably in any of the said nuts.

When the razor is in use, the handle is screwed in the nut upon the comb, and when it is desired to remove the razor-blade for stropping, the handle is screwed into the end of the blade-carrier so as to withdraw the same from the razor-head.

To hold the blade-carrier upon the handle without any liability to turn, a notch is formed in the outer end of each of its nuts and a spring-latch is located in a shoulder at the base of the screw-thread upon the handle, to engage such notch automatically

when the threaded portion of the handle is screwed nearly into the nut.

The invention involves various details of construction which will be understood by reference to the annexed drawing, in which—

Figure 1 is a front or top view of the razor-head; Fig. 2 is an end view of the entire razor; Fig. 3 is an end view of the razor-head enlarged; Fig. 4 is an end view of the blade-carrier; Fig. 5 is a longitudinal section of the blade-carrier with the end of the handle engaged in the nut and sectioned at the center line; Fig. 6 shows the end of the handle with the bolt projecting from the shoulder; and Fig. 7 shows the under side of the blank, of which the razor-head is formed by bending, as shown in Fig. 5. Fig. 8 is a plan of the razor-blade.

The device may also be used as a corn-cutter.

The comb-plate is shown with notched edge *a* having a slot *b* adjacent thereto and united to the clamping-plate *c* by a loop *d* at the rear edge of the razor-head or body. The comb and clamping-plate are provided adjacent to the loop with opposed cylindrical curves forming a nearly cylindrical bore adapted to receive the cylindrical back of the blade-carrier.

The loop *d* may be forged close to the bore, or extended rearwardly therefrom, so that its flat sides may yield elastically and thus hold the carrier firmly when inserted therein.

The blade-carrier is formed of elastic sheet-metal with a hollow cylindrical back and elastic clamping flanges *f* projected from one side of the back. One of the flanges is dented slightly inward near its front corners to form sloping projections *g* which press upon the razor-blade *h* when the same is crowded between the flanges, and thus retain it in the carrier.

A nut *i* is attached to the comb at a suitable angle, and similar nuts *j* are secured in the ends of the blade-carrier. The blade *h* is fitted to slide into the back of the holder from the front edges of the flanges *f*, and is formed with notches *k* upon its inner corners to clear the nuts *j* when the blade is inserted between the flanges.

A large notch *l* is formed at the middle of the flanges *f* to clear the fingers when gripping the blade to insert it between the

flanges, thus enabling the operator to push the blade back between the nuts into contact with the cylindrical portion of the carrier, as shown by the dotted lines *h* in Fig. 5.

5 A notch *m* is formed in the back of the carrier to permit the crowding of the blade outwardly from the flanges when it is necessary to remove the blade.

10 The handle *n* is formed with a screw-end *o* having a shoulder *p* at its base, and such screw-end is adapted to fit interchangeably the nuts upon the razor-body and upon the blade-carrier. A guide-pin *o'* is formed 15 upon the end of the screw *o* and made to fit snugly the interior of the threads, so as to guide the thread accurately in entering the nut and prevent the stripping or wear which results from crowding the screw into the 20 thread of the nuts unevenly.

20 A latch is provided movably upon the shoulder to lock the handle in either of the nuts upon the blade-carrier so as to hold the blade-carrier firmly when moved by the 25 handle in stropping the blade. The latch is shown as a spring-bolt projecting from the shoulder and operates automatically to engage a notch upon the face of the nut.

30 The bolt *q* is fitted to a socket extended into the shoulder and rests upon a spring *r* in the bottom of the socket. A thumb-piece *s* is provided in the outer side of the bolt by which the thumb-nail can retract it.

35 A notch *t* is formed in the outer end of each nut and the bolt projects from the shoulder *p* sufficiently to engage the notch when the end *o* is screwed nearly into the nut. The spring operates to press the bolt automatically into the notch so as to engage 40 the same when the shoulder has approached closely to the notched face of the nut.

To permit the shoulder to be screwed close to the nut, the bolt may be retracted by the finger and held from entering the notch *t* 45 until the shoulder is crowded against the nut, as shown at *p'* in Fig. 5.

The construction of the bolt and its retention in the socket is facilitated by making the body of the handle *n* with a socket 50 at its outer end and mounting the bolt in a shank *n'* which is inserted almost wholly in such socket.

The groove for the bolt extends to the side of the shank, and it may thus be laid in the 55 groove between the spring *r* and the end of the groove, and then held in place by fitting the shank into the socket in which it is permanently secured.

60 It is obvious that the blade can be stropped if the blade-carrier has a nut *j* in one end only, but the provision of two nuts enables the operator to remove the blade from the razor-head in either direction that he may prefer, thus accommodating either right-handed or left-handed persons.

It will be observed that the hollow cylindrical back of the blade-carrier enables it to perform two functions, first, to receive cylindrical nuts in the ends, where they are readily held by solder; and second, to fit the cylindrical bore in the body or razor-head. 70

A particular construction of the clamp-plate *c* is shown in Fig. 3 with the purpose of guarding the blade more effectively when used in shaving. 75

The forward edge of the clamp-plate is extended close to the edge of the blade, to permit only a small projection of the blade between the clamp-plate and the comb so that the tipping of the razor at an improper angle either upward or downward brings 80 the comb or clamp-plate in contact with the skin and prevents the cutting edge from operating. This extension of the clamp-plate close to the edge of the blade thus 85 forms a considerable safeguard in the use of the razor.

It will be observed in Fig. 3, that the comb-plate *a* bears a relation to the razor-blade wholly different from the clamp-plate 90 *c*, or any construction in which the edge of the blade is carried by projecting through a mere slot. The edge of the comb-plate *a* is curved away from the blade so that it may rest and move smoothly upon the skin of 95 the user to support the razor in the shaving operation; but the clamp-plate *c* is not curved away from the razor-blade but lies close to it, and extends close to its edge so as to contact with the skin at intervals 100 whenever the operator tips the razor-head to an unsafe angle. Each of these parts thus guards the edge of the razor in a different manner.

I am aware that razor-heads and blade-carriers have been formed of sheet-metal, and that a razor-handle has been fitted interchangeably with the razor-head and razor-blade, though not by the means shown herein, and I do not therefore claim such constructions broadly, but the particular features of construction which are defined in my claims. 105

Having thus set forth the nature of the invention what is claimed herein is:

1. In a safety razor, the combination, with a blade-carrier having a hollow cylindrical back with elastic gripping flanges extended therefrom, and a cylindrical nut secured within the end of the back, of sloping projections upon the inner side of one of the flanges at its corners, and a razor-blade having a notch in its inner corner to clear the said nut and pressed elastically upon by the sloping projections to retain it in the carrier when inserted into the back from the front edges of the flanges. 120

2. In a safety razor, the combination, with a blade-carrier formed of sheet-metal with a hollow cylindrical back and gripping 125

flanges extended from one side of the same to carry a razor-blade, of a nut secured in the end of the back having a notch in its outer end, and a handle having a screw and shoulder to engage such nut with a latch movable upon the shoulder adapted to automatically engage the notch as the shoulder approaches the face of the nut.

3. A safety razor, having a body comprising a comb and clamping-plate united by a loop and having opposed curves adjacent to the loop forming a cylindrical bore, a sheet-metal blade-carrier having a cylindrical back with gripping flanges to carry a razor-blade, a handle having a screw and shoulder near the end, nuts upon the body of the razor and in the end of the blade-carrier to interchangeably fit the screw upon the handle, the nut upon the blade-carrier having a notch in its outer face and a latch movable upon the shoulder to automatically engage the notch in the nut to hold the handle from rotation.

4. A safety razor having a body comprising an integral comb and clamping-plate 25 with a nearly cylindrical bore near their junction, a sheet-metal blade-carrier having a hollow cylindrical back with gripping flanges to carry a razor-blade, a nut secured in the end of the back having a notch in its 30 outer face, another nut upon the body of the razor, a handle having a screw and shoulder to interchangeably engage such nuts, a bolt-socket extending inwardly from the shoulder with a spring in the bottom thereof, a sliding bolt fitted to the socket upon the spring and adapted to engage the notch in the nut, and a thumb-piece for retracting the bolt to disengage the handle from the nut.

In testimony whereof I have hereunto set 40 my hand in the presence of two subscribing witnesses.

ACMILL BIPPART.
